UNITED STATES PATENT OFFICE.

MORRIS J. O'CONNOR, OF COURtenay, NORTH DAKOTA.

RAILWAY-RAIL JOINT.

No. 913,839.

Specification of Letters Patent.

Patented March 2, 1909.

Application filed March 7, 1908. Serial No. 420,105.

To all whom it may concern:

Be it known that I, MORRIS J. O'CONNOR, a citizen of the United States, residing at Courtenay, in the county of Stutsman and 5 State of North Dakota, have invented new and useful Improvements in Railway-Rail Joints, of which the following is a specification.

My invention relates to railway rail joints, 10 and its primary object is the provision of a device of this character which will prevent the ends of the rails from having any relative movements, thereby preventing the rounding of the ends of the rails and avoiding low 15 joints.

A further object of my invention is the provision of a rail joint which will obviate the necessity of the use of fish plates or angle bars, and which is simple, durable and efficient. 20

With the above and other objects in view, the invention consists in the construction, combination and arrangement of parts hereinafter fully described, claimed and illustrated in the accompanying drawing, wherein:

Figure 1 is a view in side elevation, illustrating a rail joint constructed in accordance with my invention. Fig. 2 is a bottom plan view of the rail joint, and Fig. 3 is a perspective view of one end of a rail equipped with a joint member constructed in accordance with my invention.

Referring to the drawing by reference numerals, 1 designates the bases, 2 the webs 35 and 3 the heads of railway rails of the usual form and construction.

Joint members 4 are secured to the bases 1 and project beyond the ends of the rails beneath the plane of the bases. The joint 40 members 4 have transverse extents equal to about one-half the width of the bases of the rails and each is arranged on opposite sides of the longitudinal center of the rails, whereby when the rails are assembled, the joint 45 member of one rail will fit beneath the base of the other rail. As the end of one rail rests upon the joint member of the other rail, it should be apparent that the ends of the rails will be prevented from having any relative 50 vertical movements. The joint members 4 are provided with elongated openings 5 for the reception of bolts 6 which, together with nuts 7, prevent the ends of the rails from

having any relative horizontal movements. Portions of the under sides of the joint members 4 are flat, so that they may rest upon a tie, as shown in Fig. 1 of the drawing, said tie supporting the rails at their meeting ends. The rails are spiked to the ties in the usual manner.

It should be apparent from the above description taken in connection with the accompanying drawing, that I provide a rail joint which will prevent the ends of the rails from having any relative movements, which 65 obviates the necessity of the use of fish plates or angle bars, and which is simple, durable and efficient.

From the foregoing description taken in connection with the accompanying drawing, the construction and mode of operation of the invention should be understood without a further extended description.

Changes in the form, proportions and minor details of construction may be made 75 within the scope of the claims without departing from the spirit or sacrificing any of the advantages of the invention.

Having fully described and illustrated my invention, what I claim is:

1. The combination with a pair of rails, of joint members secured to the bases of the rails and projecting beyond the ends thereof, each joint member being arranged on the opposite sides of the longitudinal center of 85 the rails, whereby the joint member of one rail fits beneath the base of the other rail when the rails are assembled, bolts passing through the joint members, and nuts mounted upon the bolts.

2. The combination with a pair of rails, of joint members secured to the bases of the rails and projecting beyond the ends thereof, each joint member being arranged on opposite sides of the longitudinal center of the 95 rail, whereby the joint member of one rail fits beneath the base of the other rail when the rails are assembled, and fastening means engaging the joint members.

In testimony whereof I affix my signature 100 in presence of two witnesses.

MORRIS J. O'CONNOR.

Witnesses:

O. A. LOHRKE,
J. W. HELMS.
